UNITED STATES PATENT OFFICE.

JESS W. PECK, OF NEW YORK, N. Y., ASSIGNOR TO RILEY STOKER CORPORATION, OF WORCESTER, MASSACHUSETTS, A CORPORATION OF MASSACHUSETTS.

CHAIN GRATE STOKER.

Application filed July 9, 1925. Serial No. 42,420.

This invention relates to chain grate stokers and more particularly to the clip or grate bar which is fastened to the chain and adapted to support the fuel bed of the type shown in the patents to Harrington, Nos. 1,326,590 and 1,326,591 of December 30, 1919.

In such stokers an endless chain is used to feed fuel into the furnace combustion chamber. In this construction, two parallel chains are connected by cross bars and slidably mounted on these cross bars are a plurality of clips or specially shaped blocks adapted to serve as grates and tuyères. These clips or grate blocks are so formed and shaped that they form a substantially continuous flat surfaced fuel supporting bed and permit air to enter the fuel through tuyère passages between the individual clips.

It has been found that the grate blocks of this general type as heretofore used have certain defects which prevent an efficient operation of the furnace. Because of the peculiar shape of the block, there is a tendency for the heat of the fuel bed to burn off the ends of the block and render it necessary to shut down the stoker at frequent intervals for repairs. Also large clinkered masses tend to accumulate at the centers of the blocks thereby causing the fuel to burn unevenly.

It is accordingly the main object of my invention to overcome these difficulties and to provide a grate block or clip for a chain grate stoker which will give a long life of service and be highly efficient in its operation and which will cause an even distribution of air to the fuel and will not permit an accumulation of unburned or clinkered material to remain on the block.

With this and other objects in view as will be apparent to one skilled in the art, my invention resides in the combination of parts set forth in the specification and covered by the claim appended hereto.

Referring to the drawings, in which like reference numerals indicate like parts:

Fig. 1 is a top plan view of a portion of a chain grate surface;

Fig. 2 is a top plan view of one of the grate clips;

Fig. 3 is a side elevation of the clip;

Fig. 4 is an end elevation; and

Fig. 5 is a cross sectional view on the line 5-5 of Fig. 1.

In accordance with my invention, I propose to so shape and construct the clip that its top

surface which supports the fuel bed will be narrow and have substantially the same width throughout its entire length, and will not have a wide fuel supporting surface at its medial portion but is so formed that fuel cannot accumulate in an unburned or clinkered condition anywhere thereon. The clip is shaped to form a central top portion having arms extending parallel with each other but offset in a somewhat zig-zag fashion, which is so arranged relative to the other clips that the forward end of one clip interfits between the two rear ends of the clips mounted in an adjacent row.

The particular clip illustrated in the drawings comprises a metal body having a substantially flat top surface 10 shaped as two long rectangles of uniform width joined in an offset manner to a medial portion. Each clip has an arm composed of a vertical web 11 and a fuel supporting flange 18, and a second arm composed of a vertical web 11', a fuel supporting portion 15, and a horizontal flange 16. An enlarged slotted portion 12 is located centrally of the clip and is provided with a groove 13 adapted to be slid over a correspondingly shaped bar mounted on the chains and to be suitably fastened thereto. A transverse rib 14 strengthens the middle portion of the grate clip.

The horizontal flange 16 projects a short distance beyond the sides and the end 17 of the fuel supporting portion 15 and is spaced below the top surface 10 by a distance slightly greater than the thickness of the flange 18 on the other arm of the clip. These two flanges 16 and 18 are therefore offset relative to each other both vertically and horizontally.

It will be seen by reference to Figs. 1 and 5 that the clips are interfitted in such a way that the fuel supporting flanges 18 lap over the projecting flanges 16 and are spaced therefrom slightly in a vertical direction and that the flanges 16 are spaced somewhat horizontally, from the vertical webs 11 in order to provide for the circulation of air between the blocks. I also may provide spaced grooves or channels 19 in the sides of one of the arms, such as the portion 15, to serve as tuyère openings and insure the passage of air upwardly through the tortuous channel between adjacent clips.

These clips are so mounted on their support as shown in the patent to Harrington

No. 1,326,590 that as the clip reaches the end of its horizontal travel and turns downwardly the rear end of the clip will draw away from the front end of the adjacent clips 5 without raising above their level. Similarly, when the clip has reached the end of its return path on the underside of the chain and is turning upwardly and coming back into place to support the fuel bed, the flanges 18 10 fall down into place over the flanges 16 of adjacent clips and thereby come into place properly for supporting the fuel.

It will now be seen with reference to the drawings that the width of the upper surface which supports the fuel bed is substantially uniform throughout and that the central fuel supporting portion 20 is of about the same width lengthwise of the clip as is the transverse width of the portion 15 and 20 flange 18. This insures air being admitted through tuyère openings which are substantially the same distances apart, and air is admitted through the spaces 21 very close to the center of the top of the clip. The arms of 25 the clip are made of the same width and substantial in size so that they will not burn away readily and if they do burn to some extent there is considerable metal in the webs and other adjacent portions which will 30 carry the fuel bed and prevent a large vol-

ume of air escaping upwardly into the fire, or any considerable amount of fuel falling past the burned off portion of the clip.

Having thus described my invention, what I claim as new and desire to secure by Letters Patent is:

A grate block for a chain grate stoker comprising a unitary casting having a vertical web provided with a slot at its lower end for fastening it on a support, two parallel 40 horizontal flanges extending towards opposite ends of the block, one forming the top surface of the block and the other being located below the top surface so that the lower flange of one block may lie beneath and 45 slightly spaced from the upper flange of another block and form a tortuous passage therebetween, when the parts are normally assembled, the top of the block being shaped to form two laterally offset arms having 50 parallel sides and a top surface of substantially the same width throughout and these arms having small uniformly spaced vertical grooves on a side thereof which are arranged to conduct air from beneath the block to a 55 fuel bed supported thereon.

Signed at New York, N. Y., this third day of July, 1925.

JESS W. PECK.
